ROPE SPLICING TOOL

Elmer H. Borgelt, Dayton, Ohio

Application September 20, 1944, Serial No. 554,931

4 Claims. (Cl. 57—23)

(Granted under the act of March 3, 1883, as amended April 30, 1928; 370 O. G. 757)

The invention described herein may be manufactured and used by or for the Government for governmental purposes, without the payment to me of any royalty thereon.

The invention to be hereinafter disclosed relates to a rope splicing tool.

In rope splicing, it is customary to spread or separate the strands and weave through or between them the strands to be connected therewith or incorporated therein, all as is well understood. Various devices are used for separating the strands, one very common type being that known as a marlin-spike. The most usual form of this type is a cylindrical bar or rod having one pointed end. The pointed end is forced between the plies until they are amply spread, when it is removed and the connecting ply is inserted through the opening. With many types of rope, that is a practical method, but if the rope is a tight formation such separation is very difficult. Likewise, if the fiber is easily damaged such a method is not practical. Tow ropes used in quantity with glider planes are, in many instances, of nylon. They are very tightly twisted and their fibers are easily damaged. It is extremely difficult to separate the plies with a marlin-spike and even where that is possible, serious fiber damage is probable. Even if it be assumed that it would be practical to separate the strands with such a tool, there still remains the objection that as the tool is withdrawn there is nothing to maintain that spread condition to permit threading through of the strand of the connecting rope.

The present invention eliminates or minimizes the above and other objections and provides a simple, efficient and compact rope lacing, threading or splicing tool capable of ready low cost quantity production.

In order to more clearly disclose the construction, operation and use of the invention, reference should be had to the accompanying drawings forming part of the present application.

Throughout the several figures of the drawing, like reference characters designate the same parts in the different views.

In the drawing:

Figure 1 is a side elevation;

Figure 2 is a perspective view, applied;

Figure 3 is an elevation of a rope section with the spacing sleeve in place;

Figure 4 is a plan view of Figure 3; and

Figure 5 is a fragmentary longitudinal cross section of Figure 1, on line 5—5.

Referring to the drawing in detail 1 indicates a bar, rod or post shown as cylindrical although

any other practical shape or form may be used. A simple form or type of grip or handle 2 is disposed as a T-head, in the form of a rod of smaller diameter passed through the upper end of 1. The lower end of 1 is bored out or otherwise provided with a suitable socket 3 to freely receive the cooperating upper end of a bit shank 4. Where that bore 3 and shank 4 are cylindrical, as shown, it is necessary to prevent relative rotation or turning movement between them, as will be well understood. Where they are not cylindrical such non-rotation is prevented by their respective shapes. So, in the form illustrated, the upper end of the shank 4 is provided with a diametrical slot or notch 5 adapted to fit about or receive a pin 6 which bridges socket 3 diametrically at a short distance from its inner end. Obviously, various other driving connections between 1 and 4 may be used as desired. Bit 4, it will be noticed, may be readily slipped into and out of operative position within socket 3. On the bit shank 4 is freely and removably mounted a tubular spacing sleeve 7. Sleeve 7 should have an interior diameter approximately equal to the outer diameter of the strand which it is desired to use in splicing, for a purpose to be later disclosed. Likewise, its length should be appreciably greater than the diameter of the rope in which the splice is to be made. Sleeve 7 is carried on shank 4 between the end of 1 and a supporting shoulder 8 formed on 4. Accordingly, that part of shank 4 between 1 and 8 will be of the same length as sleeve 7. The operative part of the bit is a spiral blade 9 extending from shoulder 8 to the outer end 10. The pitch of the spiral should be approximately that of the rope strands of the rope on which the tool is to be used. At the upper end, as will be clearly seen, the spiral merges into the shoulder 8. The radial width of the shoulder 8, it will be noticed, is approximately that of the radial thickness of sleeve 7, so that the outer edge of shoulder 8 and the outer face of sleeve 7, when assembled, are in substantial alignment. The lower end 10 of the spiral blade is made by cutting substantially diametrically across the spiral 9 and rounding off the corners. The edges of the blade end should be smoothed or rounded to avoid all possible damage to the rope fibers when the tool is being used, as will hereinafter appear.

The operation of the invention is as follows: The rope in which the splice is to be made is firmly held or secured in any suitable manner and the assembled tool, as in Figure 1, is inserted at the desired point, the end 10 making the en-

trance. By applying pressure and turning blade 9 as you would a cork screw, the blade will follow through between the strands, spreading them apart to the diameter of shoulder 8 and sleeve 7. As the tool continues through the rope, the sleeve 7 and enclosed shank 4 will be between the rope strands with the ends of sleeve 7 extending at opposite sides of the rope. When this point is reached, the rod and handle 1 and 2 are withdrawn from one end of sleeve 7 and the shank 4 with blade 9 are withdrawn from the opposite end. This leaves sleeve 7 between and separating the strands and extending appreciably on opposite sides of the rope. It maintains an opening between the strands after the splicing tool has been removed, so that the connecting strand may be readily fed through. And, of course, as the splicing strand is fed through it will carry through with it the sleeve 7 which may then be readily slipped from its end and reassembled in the tool.

In order to prevent accidental slipping out or dropping out of the shank 4 and the sleeve 7, a friction holding device is provided. In the preferred form this is a small ball bearing 11 reciprocably mounted in a radially disposed bore or socket 12 in the shank 4 and maintained in operative position by a small coil spring 13. At the outer end socket 12 is restricted by peening over the edge to intercept the ball. In this way, the ball, under spring pressure, will yieldingly engage the inner wall of socket 3. Likewise, it will have the same yielding or frictional engagement with sleeve 7, preventing the sleeve from accidentally slipping off of the shank. It provides a simple frictional holding device. Other frictional holding devices may be similarly used, though that shown is the preferred one.

The strands are quickly and easily separated and definitely maintained amply separated during splicing and there is no damage to the fiber during the entire operation.

It is thought that the construction, operation and use of the invention will be clear from the preceding detailed description.

Many changes may be made in the construction, arrangement and disposition of the various parts of the invention within the scope of the appended claims without departing from the field of the invention and it is meant to include all such within this application wherein only one preferred form has been illustrated by way of example and with no thought or intention of, in and degree, limiting the claims thereby.

Having thus described my invention, what I claim and desire to protect by Letters Patent is:

1. A rope splicing tool comprising a handle provided with a concentrically disposed socket ex-

tending longitudinally into one end thereof, a bit shank of substantially the same cross sectional area as that of said socket removably mounted in said socket in non-revolvable relation to said socket, said shank being provided with a radially extending shoulder disposed at a distance from the adjacent handle end, in assembled relation, and a tubular sleeve removably mounted on said bit shank between said shoulder and said adjacent handle end.

2. A rope splicing tool comprising a handle provided with a concentrically disposed socket extending longitudinally into one end thereof, a bit shank of substantially the same cross sectional area as that of said socket removably mounted in said socket in non-revolvable relation to said socket, said shank being provided with a radially extending shoulder disposed at a distance from the adjacent handle end, in assembled relation, a tubular sleeve removably mounted on said bit shank between said shoulder and said adjacent handle end and means carried by said bit shank and yieldingly engaging the adjacent inner wall of the aforesaid socket.

3. A rope splicing tool comprising a handle provided with a concentrically disposed socket extending longitudinally into one end thereof, a bit shank of substantially the same cross sectional area as that of said socket removably mounted in said socket in non-revolvable relation to said socket, said shank being provided with a radially extending shoulder disposed at a distance from the adjacent handle end, in assembled relation, a tubular sleeve removably mounted on said bit shank between said shoulder and said adjacent handle end and means carried by said bit shank and disposed to yieldingly engage said sleeve and prevent accidental removal.

4. A rope splicing tool comprising a handle provided with a concentrically disposed socket extending longitudinally into one end thereof, a bit shank of substantially the same cross sectional area as that of said socket removably mounted in said socket in non-revolvable relation to said socket, said shank being provided with a radially extending shoulder disposed at a distance from the adjacent handle end, in assembled relation, a tubular sleeve removably mounted on said bit shank between said shoulder and said adjacent handle end, and means carried by said bit shank and yieldingly engaging the adjacent inner wall of said socket to prevent accidental removal of said bit shank therefrom, said last named means being disposed to yieldingly engage said sleeve and prevent accidental removal.
